CHARLES JOSEPH PFRIEMER, OF NEW YORK, N. Y., ASSIGNOR TO CHAS. PFRIEMER, INC., OF NEW YORK, N. Y.

STAPLING-MACHINE.

1,149,944.

Specification of Letters Patent. Patented Aug. 10, 1915.

Application filed July 23, 1914. Serial No. 852,639.

To all whom it may concern:

Be it known that I, CHARLES J. PFRIEMER, a citizen of the United States, and a resident of the city of New York, borough of the Bronx, in the county of Bronx and State of New York, have invented a new and improved Stapling-Machine, of which the following is a full, clear, and exact description.

This invention relates to wire working machinery, and has particular reference to stapling machines.

Among the objects of the invention is to provide a machine adapted especially for the securing or fastening of wire staples used in the manufacture of piano hammers for securing the points or tips of the felt covering to the hammer molding. I wish it distinctly understood, however, that while this specification discloses particular reference to piano hammers, the machine is obviously adapted, either as a whole or in many of its parts, to the operation on many other and various type of work. The term "work", therefore, as may be used herein, will be understood as being adapted for an interpretation broad enough to cover not only a piano hammer being stapled, but any other device to which the machine may be suited.

Stated more specifically, one of the principal objects of the invention is to provide a means for quickly and accurately twisting the prongs of a wire staple which has been applied to a piece of work, snipping off the points or untwisted portions thereof, and then subsequently bending over or clenching the portion of the staple thus twisted, whereby an indefinite number of pieces of work may be treated in a uniform manner as to application of the staples thereto and the appearance of the finished product.

A further object of the invention is to provide means for operating upon the work in the manner above indicated in a substantially automatic manner and hence at a very rapid rate compared with the hand operation.

The foregoing and many other objects of the invention will hereinafter be more fully described and claimed and illustrated in the drawings forming a part of this specification in which like characters of reference indicate corresponding parts in all the views, and in which—

Figure 1 is a vertical longitudinal and

substantially central sectional view of a preferred embodiment of this invention, the section being taken on the line 1—1 of Fig. 2; Fig. 2 is a plan view of the same, the guide post, however, being in section; Fig. 3 is a vertical transverse section on the line 3—3 of Fig. 2; Fig. 4 is a horizontal sectional detail on the line 4—4 of Fig. 3; Fig. 5 is a side elevation of a detail of the machine; Figs. 6 and 7 are detail plan views of the machine in progressive stages of operation; Fig. 8 is a sectional detail on the line 8—8 of Fig. 2; and Fig. 9 is a perspective view of a staple adapted to be acted upon by this machine.

Referring more particularly to the drawings, I show at 10 a bed plate adapted to be secured in horizontal position to a bench or table 11 of any suitable character and in front of which, or at the right of Fig. 1, the operator is supposed to be located. At the front end of the bed plate is shown at 12 an upwardly projecting flange or guard, and to the rear of the guard is an upwardly projecting post 13 having a hole 14 extending therethrough from front to rear, the front portion of the hole being reamed out or flared so as to gather and guide the points or prongs of the staple to and through the comparatively small rear end of said hole. The post 13 may be secured to the bed plate in any suitable manner and is thereby held in rigid fixed position.

At 15 I show a carriage movable toward and from the post 13 by any suitable means. As shown herein, the carriage is adapted to slide in right lines, being guided along the bed plate by means of a pair of flanges 16 projecting toward each other over flanges 15' projecting laterally from the bottom of the carriage. The guard 12 limits the movement of the carriage forwardly to idle position and the post 13, or a pillar 13^a, to which the post is herein shown as being connected, limits the rearward movement of the carriage. The carriage 15 is designed to carry the work herein shown as a piano hammer H with a staple S passed through the points of the felt F and the molding M into position with the points s of the staple projecting through the hole 14. The hammer is held temporarily in position on the carriage by resting upon a shelf 17 at the bottom of the hammer, the front edge of the hammer bearing forwardly against

an anvil 18 and the striking end or point of the hammer resting against an adjustable stop 19 carried by a set-screw 20 supported in turn by means of a lug 21 secured to the 5 right-hand portion of the carriage. The loop or crotch portion of the staple bears directly against the face of the anvil 18 when the hammer is carried in proper position on the carriage. The adjustable screw 10 20 adapts the machine for hammers of different sizes and shapes, depending upon the various makes of pianos or the differences in the various registers for the same set of hammers. At 22 I show a finger piece 15 which projects upwardly from the carriage and serves to assist the operator in the manipulation of the carriage and holding the work in position thereon. A trip lug 23 projects laterally from one side of the carriage.

Secured to the upper portion of the bed plate in the rear of the post 13 is a frame 24 having a plurality of upwardly projecting bearings 25 and 26 in which is journaled a 25 substantially horizontal shaft 27. A pair of collars 28 serve as one means for preventing longitudinal movement of the shaft in said bearings. A pinion 29 is secured to the shaft preferably closely adjacent the rear 30 face of the bearing 26. In front of the bearing 26 is provided a cone 30 which is non-rotary independently of the shaft, but is slidable longitudinally thereon by any suitable means. This cone is provided with 35 two cams or shouldered portions 31 and 32 adjacent its front end or apex, the shoulder 32 being of larger diameter than the shoulder 31. This cone is shown adapted to be operated forwardly and rearwardly along 40 the shaft by means of a yoke 33 operating in the grooved rear portion of the cone. The yoke is shown secured to and extending laterally from a sleeve 34 slidable along a rod 35 parallel to the shaft 27 and supported upon a bracket 36 secured to the bed plate 10. Any suitable means may be provided to tend to hold the yoke and cone adjacent the bearing 26. The means shown for this purpose comprises a pair of springs, 45 one spring 37 being coiled about the shaft 35 and acting between one end of the bracket at one end and the sleeve at the other end, and another spring 38 on the opposite side of the shaft 27 is connected at one end to a 50 fixed point 39 and at the other end at 40 to one arm of the yoke. These two springs co-operate with each other to insure a reliable action upon the yoke.

At the front end of the shaft is secured a 60 head 41 in which are pivoted at 42 a pair of nipper jaws 43. These jaws are arranged preferably in the form of levers of the first class, and are provided at their front ends with lips 44 which are adapted initially to 65 grasp the prongs *s* after they have been pro-

jected through the hole 14, this action of the nippers resulting from the coöperation between the shoulder 31 of the cone and the rear ends of the jaws, a pair of adjustable studs 45 being provided for the purpose of 70 providing a satisfactory operation of the nippers.

The numeral 46 indicates a combined rack and cam member adapted to reciprocate vertically at one side of the shaft 27. The 75 rack teeth 47 coöperate with the pinion 29, and when the member 46 is forced downwardly the pinion and shaft are rotated in a clockwise direction, as viewed from the front. Any suitable means may be provided 80 to operate the rack member. The illustration of such means here given is a foot-lever 48 pivoted at 49 to the lower end of the rack and having its rear end pivoted at 50 to some stationary support. The lever 48 is 85 acted upon by a strong spring 51 shown as connected between the table 11 and the lever, and the tendency of the spring is to restore the lever to its normal elevated position. While a downward thrust upon the 90 foot-lever initiates a rotation of the shaft 27 and nippers 43 substantially simultaneously therewith, the cam 52 of the rack member acts against the yoke 33 causing the cam shoulder 31 to cause the nippers to grasp 95 the points *s*, and during the continued downward movement of the rack member and rotation of the nippers, the projecting prongs of the staple are twisted together securely, as shown in Fig. 6. When the rack 100 member approaches the limit of downward movement, the second cam 53 engages the yoke, giving a further forward impulse and causing the lips 44 of the nippers to snip off the untwisted points of the staple. While 105 the lever 48 is moving downwardly, power is being stored in the main spring 51 and also in the springs 37 and 38 which act subsequently upon the yoke to restore it to normal position, carrying the cone 30 rearwardly so as to allow the nipper lips to open. The means shown for insuring the opening movement of the nippers consists preferably of a comparatively light spring 110 54 extending transversely of the head 41 and secured to the two jaws in the rear of the pivots 42. The rack member 46 is guided in a fixed bracket 46' secured to the bed plate in the rear thereof and at the side opposite the pinion 29. The upward movement of the rack member is shown in this instance as being limited by means of a stop 55.

At 56 I show a mallet whose arm is secured to the upper end of a vertical rock shaft 125 57. Secured to the upper end of the rock shaft 57 between the mallet arm and the bed plate 10 is a hub 58 having at its lower end a horizontally extending catch 59. A spring 60 surrounds the hub 58, one end of the 130

spring being connected to the mallet arm and the lower end of the spring is engaged around or over a lug 61 secured to the bed plate. To the lower end of the rock shaft 57 is secured a finger 62, which projects laterally therefrom or in a horizontal plane and substantially at right angles to the vertical plane of the catch 59. A bell-crank lever 63 is pivoted at 64 beneath the bed plate 10 and is movable in a vertical plane by means of a link 65 extending between the foot lever 48 and the rearwardly extending arm 63' of the bell crank. The bell-crank lever 63, shown best in Figs. 3 and 4, is provided 15 with a laterally projecting finger 66 which is adapted to engage with the finger 62 and cause rotation of the rock shaft in a counterclockwise direction looking downward, when the main spring 51 acts upon the lever 20 48 to restore the parts to the normal position shown in Figs. 1, 2 and 3. This action upon the rock shaft 57 serves to set the mallet in the position shown in Fig. 2, with the spring 60 under tension. This position of the mallet is maintained by means of a trigger 67 pivoted upon the vertical pivot 68 and acted 25 upon by a leaf spring 69. This trigger comprises a shoulder 70 engaging directly with the catch 59 and also includes a finger 71 projecting beyond and to the right of the shoulder 70 which is adapted to be struck by the trip lug 23 on the carriage when the carriage is moved forwardly. When the foot-lever 48 is depressed by the operator, 30 the link 65 connected to the bell-crank will swing the finger 66 forwardly away from the finger 62. Hence, when the trigger 67 is tripped by the lug 23, the mallet will be free to be thrown forcibly around in a clockwise direction, as shown in Fig. 7, by means 35 of the stored force of the spring 60. At the moment the trip lug 23 trips the trigger 67, the carriage is on its return forward movement after the staple has been twisted and 40 has its points snipped off. As may be seen, therefore, from Fig. 6, there is left a short twisted portion projecting from the rear face or edge of the hammer H which the mallet 56 bends or clenches over toward 45 the point of the hammer, as shown in Fig. 7. The striking face of the mallet is provided with a pair of parallel ribs 72 which form a groove 73 within which the end of the coiled or twisted portion of the staple is received, thereby insuring that said twisted portion of the staple will always be bent in precisely the same direction. The felt F is sufficiently flexible to allow the ribs 72 to embed themselves sufficiently to insure that 55 the staple will be clenched or forced well down within the surface of the hammer.

The mechanism being thus described in detail, the operation may be briefly summarized as follows: The operator stationed 60 in front of the machine applies the ham-

mers H in succession to the carriage 15, each hammer having been previously bored and supplied with a staple as shown in Figs. 1 and 2. The hammer is applied to the carriage with the loop portion of the staple 70 against the face of the anvil 18, and the member 19 is adjusted so as to bring the points of the staple in alinement to be gathered by and fed through the flaring hole 14. After the points of the staple are carried through the hole 14 by the movement of the carriage as from the position of Fig. 2, the operator will depress the foot lever 48, then starting the operation of the combined rack and cam member 46, causing the 75 nippers to grasp and twist the staple, as shown in Fig. 6, and the final portion of the movement of the rack member causing the snipping off of the points, as above described. When the carriage is drawn forwardly or away from the post 13, the mallet will be tripped, which serves to clamp the twisted portion of the staple, as shown in Fig. 7. At this moment the foot-lever 48, being released and allowed to return 80 upwardly to its normal position, will permit the main spring 51, whose strength is superior to that of the spring 60, to return the mallet to normal position, as shown in Fig. 2. The finished hammer will then be removed from the carriage and another put in its place ready for another operation of the machine.

Having thus described my invention, I claim as new and desire to secure by Letters Patent:

1. In a stapling machine, the combination of a post having a guide hole therethrough, a carriage movable toward and from said post, means to hold the work in a substantially fixed position on the carriage with the staple prongs directed through said hole, means on the opposite side of the post from the carriage to grasp the prongs and twist them together, and means to cause the 100 grasping means to snip off the untwisted points of the prongs.

2. In a stapling machine, the combination of a guide member and a carriage movable relatively toward and from each other, means to support a hammer with a staple therein upon the carriage in position to cooperate with said guide member, means on the opposite side of the guide member from the carriage to grasp and twist the staple 105 prongs, and means acting subsequently upon the twisted staple to bend the same down snugly upon the hammer.

3. In a machine of the class set forth, the combination of a rotary shaft, gripping means carried by the shaft, means to support a hammer with a staple therein and carry the same toward the shaft so as to bring the points of the staple into position to be grasped by the gripping means,

and means acting upon the shaft and gripping means to cause the gripping means to act upon the staple and simultaneously twist the same.

5 4. In a machine of the character set forth, the combination of a rotary shaft, a pair of nippers carried by the shaft, means to carry work to be stapled into position to be grasped by the nippers, means acting upon 10 the shaft to cause rotation thereof and the gripping action of the nippers simultaneously, and means acting subsequently to clenched the twisted portion of the staple.

5 5. In a machine of the character set forth, 15 the combination of a rotary shaft and a carriage movable relatively to and from each other, gripping means carried by the shaft, means to support a piece of work upon the carriage with a staple in position to be 20 grasped by the gripping means, means acting upon the shaft and gripping means to simultaneously cause the gripping means to seize the staple prongs and rotate the shaft, causing the twisting of the prongs, and a 25 swinging mallet adapted to subsequently clenched the twisted staple after the gripping means and carriage are separated.

5 6. In a machine of the character set forth, 30 the combination of a carriage, means to support a piece of work thereon to be stapled, gripping means adapted to seize the staple when the carriage is moved in one direction, means to rotate the gripping means to twist the staple after being seized, a spring-operated 35 mallet adjacent the carriage, and means made operative by the movement of the carriage in the opposite direction to cause the mallet to operate to clenched the twisted portion of the staple.

5 7. In a machine of the character set forth, 40 the combination of a rotary shaft, a pair of nippers pivoted thereon and adapted to be rotated thereby, means to support a staple in position to be grasped by the nippers, 45 means to rotate the shaft and nippers, and means acting simultaneously with the rotation of the shaft to cause the nippers first to seize the staple and twist it and subsequently snip off the untwisted points thereof.

5 8. The combination of a rotary shaft, a 50 pair of nippers carried by the end of the shaft and adapted to move relatively to each other in a plane coinciding with the axis of the shaft, means to support a piece of work 55 with a staple in position to be grasped by the nippers, means to rotate the shaft, a conical member mounted upon the shaft and slideable therealong, and means acting from the shaft rotating means to cause the conical member to act upon the nippers to grasp the staple and twist it simultaneously with the rotation of the shaft.

5 9. In a stapling machine, the combination 60 of a rotary shaft, a pair of nippers pivoted 65 to the end of the shaft and adapted to be

rotated therewith, means to support a piece of work with a staple in position to be grasped by the nippers, a double conical member splined to the shaft and movable toward and from the nippers, and means 70 serving to rotate the shaft simultaneously with the action of the nippers to grasp the staple by virtue of one of the cone members, the other cone member acting subsequently to cause the nippers to snip off the 75 untwisted points of the staple.

10 10. In a machine of the character set forth, the combination of a rotary shaft, a pair of nippers carried by the same and caused to rotate therewith around the axis of 80 the shaft, means to support a piece of work with a staple therein in position to be grasped by the nippers, means movable with respect to the nippers and adapted to act thereon initially to cause the nippers to seize 85 the staple and subsequently to snip off the points thereof, and means to rotate the shaft and nippers.

11 11. In a machine of the character set forth, the combination of a shaft, means to 90 rotate the shaft, gripping means carried by the shaft and adapted to be rotated therewith, means to support a piece of work with a staple in position to be grasped by the gripping means, and means actuated by the 95 shaft rotating means whereby the gripping means are caused first to grasp and twist the staple and subsequently to snip off the untwisted points thereof.

12 12. In a machine of the character set 100 forth, the combination of a pair of nippers, means to support a piece of work with a staple in position to be grasped by said nippers, means acting upon said nippers to cause the rotation thereof, and other means 105 acting upon the nippers causing them first to grasp the staple and twist the same during the rotation of the nippers and subsequently to cause them to snip off the untwisted points of the staple.

13 13. The combination of a rotary shaft, means to rotate the shaft, a pair of nippers carried by the shaft and rotatable therewith, means to hold a piece of work with a staple 115 therein in position to be grasped by the nippers, a double conical member slideable along the shaft, the two conical portions of the members acting in succession to cause the nippers to grasp the staple and subsequently to snip off the untwisted points of 120 the staple, and means acting from the shaft rotating means to make the double conical member effective.

14 14. In a machine of the character set 125 forth, the combination of a shaft, means to support the shaft for rotation around a fixed axis, a pair of gripping nippers carried by the shaft and rotatable therewith, means to rotate the shaft, said last-mentioned means including a combined rack and cam member 130

movable at an angle to the axis of the shaft, means slidable along the shaft to cause the gripping means to seize the staple, and means to cause the cam portion of said combined member to act upon said slidable means, substantially as set forth.

15. In a machine of the character set forth, the combination of a rotary shaft, gripping means carried thereby and rotatable therewith, means to support a piece of work with a staple therein in position to be grasped by the gripping means, a combined rack and cam member movable at right angles to the axis of the shaft to cause the rotation thereof and of the gripping means, means acting from and in conjunction with the shaft rotating means to cause the gripping means to act upon the staple, means to act positively upon the rack to effect the movements aforesaid, and means acting subsequently upon the rack and associated parts to restore them to normal position.

16. In a machine of the character set forth, the combination of a rotary shaft, gripping means carried thereby and rotatable therewith, means including a rack to cause rotation of the shaft, a lever connected to the rack for positive movement thereof in one direction, a spring acting upon said lever to move the rack in the opposite direction automatically, means movable toward and from the gripping means adapted to support a piece of work with a staple in position to be grasped thereby and twisted by virtue of the rotation of the shaft and gripping means, a power mallet adapted to act upon the staple after being twisted, and means between said lever and said mallet to automatically cause power to be stored therein substantially as set forth.

17. In a stapling machine, the combination of a rock shaft, a power mallet secured to said rock shaft and adapted to swing in an arc of a circle around the axis thereof, a spring associated with the mallet and adapted to cause the swinging thereof in one direction, means acting upon the rock shaft to swing the mallet in the opposite direction, putting the spring aforesaid under tension, trigger mechanism serving to hold the mallet in set position, a carriage movable in proximity to the mallet and rock shaft adapted to carry thereon a piece of work being stapled, and means to cause the tripping of said trigger mechanism at a predetermined time from the carriage to make the operation of the mallet effective.

18. In a machine of the character set forth, the combination of a bed plate, a rock shaft extending therethrough and journaled therein, a power mallet secured to one end of the rock shaft and movable in an arc of a circle around the axis thereof, a spring acting between the mallet and the bed plate to cause the mallet to move forc-

bly in one direction, automatic means acting upon the other end of the rock shaft to cause movement of the mallet into set position, putting said spring under tension, trigger mechanism including a catch 59 to 70 hold the mallet in set position, a carriage adapted to support a piece of work in proximity to the mallet and movable along the rock shaft, and means projecting from the carriage acting while the carriage is movable in one direction to trip the trigger mechanism, substantially as set forth.

19. In a stapling machine, the combination of a bed plate, a carriage slidable along the bed plate and adapted to support a piece of work in position to be stapled, a rock shaft journaled in the bed plate and projecting therefrom with its axis at right angles to the plane of movement of the carriage, a power mallet secured to the rock shaft and movable in an arc of a circle therewith around the axis thereof, a spring acting between the mallet and the bed plate to cause the quick movement of the mallet in one direction, trigger mechanism including a catch 59 serving to hold the mallet in set position with the spring under tension, automatic means of superior force to the spring aforesaid to move the mallet into set position storing power in said spring, said automatic means including a finger secured to another portion of the rock shaft and extending therefrom at an angle to the catch aforesaid, and means operative from the carriage when moved in a certain direction to trip the trigger mechanism at a predetermined time to set the mallet free, substantially as set forth.

20. In a stapling machine of the character set forth, the combination of a bed plate, a carriage movable therealong and adapted to support a piece of work in position to be stapled, said supporting means including an anvil member against which the loop portion of the staple abuts, a power mallet adjacent the carriage and movable toward said anvil member, a spring associated with the mallet tending to move it as aforesaid, automatic means of strength superior to said spring serving to move the mallet in the opposite direction into set position, trigger mechanism serving to hold the mallet in set position, and means projecting from the carriage whereby the movement thereof in one direction at a predetermined time will trip the trigger mechanism, allowing the mallet to swing under the force of its spring so as to act upon the work in conjunction with said anvil member.

21. In a stapling machine, the combination of a power mallet movable forcibly in a certain path, a carriage adapted to support a piece of work with a wire staple therein and movable with the staple along said path, and means operated from the car-

1,149,944

riage during its movement to cause movement of the mallet at a predetermined time, the face of the mallet being provided with a groove 73 serving to receive the projecting portion of the staple and cause it to be clenched in a predetermined direction.

In testimony whereof I have signed my

name to this specification in the presence of two subscribing witnesses.

CHARLES JOSEPH PFRIEMER.
